UNITED STATES PATENT OFFICE.

KEDAR HARTLEY, OF PHILADELPHIA, PENNSYLVANIA, ASSIGNOR, BY DIRECT AND MESNE ASSIGNMENTS, OF ONE-HALF TO JOSEPH HANSON, OF SAME PLACE.

LOOM FOR WEAVING CHENILLE AND FRINGE.

SPECIFICATION forming part of Letters Patent No. 396,205, dated January 15, 1889.

Application filed April 22, 1887. Serial No. 235,726. (No model.)

To all whom it may concern:

Be it known that I, KEDAR HARTLEY, a citizen of the United States, residing at Philadelphia, in the county of Philadelphia and 5 State of Pennsylvania, have invented certain new and useful Improvements in Looms for Weaving Chenille and Fringe; and I do declare the following to be a full, clear, and exact 10 description of the invention, such as will enable others skilled in the art to which it appertains to make and use the same, reference being had to the accompanying drawings, and to the letters and figures of reference marked thereon, which form a part of this specification. 15

My invention relates to looms, and has more especial reference to that class of looms used in the manufacture of fabrics which are intended to be cut into longitudinal strips to 20 form chenille filling or woof for use in making rugs.

The main points of construction which constitute the novel features of the present invention may be enumerated as follows: first, 25 the device for holding the weft or filling threads; second, the means for causing any one of a series of such devices to be elevated into position beside the warp-threads; third, means for adjusting such device laterally when it is adjusted vertically; fourth, a cutting device for severing said weft-thread at or 30 near the holding device after the nippers have drawn it through the shed; fifth, means for giving the pattern-card and its supporting 35 and feeding means the necessary lateral adjustment to receive a needle from any one of two or more vertical lines of needles, and various details of construction and combinations 40 of parts constitute other points of improvement, as will be hereinafter described, and pointed out in the claims.

The accompanying drawings illustrate what I consider the best means for carrying my invention into practice.

45 Figure 1 is a side elevation of the loom complete with all my appliances and improvements attached. Fig. 2 is a front elevation of the same. Fig. 2^a is a detail view of the mechanism for operating the drum from which 50 the thrust-arm is actuated. Fig. 3 is a detail

view, partly in section, showing particularly the devices for holding and cutting the filling-threads. Fig. 4 is a partial plan of the devices shown in Fig. 2. Fig. 5 is a side elevation of the devices shown in Fig. 3, taken from 55 the left hand thereof, and in addition means for holding a selected weft-holder elevated. Fig. 5^a is an enlarged view of a thread-holder. Fig. 6 is a side elevation, on an enlarged scale, of the Jacquard mechanism and card. Fig. 60 7 is a section of Fig. 6 on the line X Y, looking down. Fig. 8 is a detail view of a part of the Jacquard mechanism, taken from Fig. 1, looking in the direction of arrow No. 1. Fig. 9 is a detail of a portion of the card-carrying device. Fig. 10 is a vertical section on the line 65 V W of Fig. 6.

Similar letters and figures of reference indicate corresponding parts in all the figures where they occur.

A is the fixed frame of the loom, and A' the harness mechanism, which operates the warp-threads, and which is of the ordinary style well known in looms and need not be particularly described here.

A² represents the finished fabric, which is afterward cut into strips for furnishing the filling for rug-weaving. The character of this filling is well understood, it consisting of two or more warp-threads and a series of short 80 weft-pieces, which form the nap of rugs, the warp-threads of the loom herein shown being disposed in sets or pairs, with a short distance between each two adjacent sets or pairs, which space affords a line to be cut by suitable machinery to furnish the nap of rugs, as aforesaid, when such strips are woven into rugs; but, as the particular use of the goods produced is not essential to the construction and operation of the machine herein described, it 85 will be understood in the outset that I do not make this explanation in order to limit the uses of my machine, but simply to give a clearer understanding of its parts and purposes.

C C are the take-up rolls for the goods after being woven. These take-up rolls are of the well-known form and are placed and operated in the usual way.

I will first describe the thread-holding de- 100

5 vices and the means for operating them. These devices, of which there may be any desired number, consist of a standard or stem, *d*, on the upper end of which is a head having an inward projection, *d'*, having a channel or groove open on top and registering with an opening, *d²*, through the head of the stem, and a hinged arm, *d³*, which drops by gravity down into the said groove or channel and forms a tension for the weft-thread *d^x*, which is passed through the opening *d²* and lies in the said channel under the arm. The front end of the arm *d³* is finished with a downwardly-projecting beak or extension, *d⁴*, which drops over the end of the projection *d'* and further increases the tension upon the weft-threads, the under side of the beak being grooved to hold the weft yarn or thread *d^x* centrally under it. The rear end of hinged 50 arm *d³* is pivoted or hinged in a portion of the head of the stem, which projects or extends above the projection *d'*. A set or series of these thread-carriers, which, as a whole, I shall denominate or mark *D* for sake of peculiarity in the further description, are held in a sliding frame or carriage, *E*, which is mounted upon a bar or way, *e*, held in the fixed frame of the machine. Any number of holders may be employed, according to the 55 number of colors designed to be used.

The holders *D* are held in the carriage *E* with liberty to move up and down therein, while the carriage is capable of lateral movement on the bar *e*.

5 The vertical movement of the holders is a separate and independent action brought about in each holder separately and independently by means of connections from the Jacquard harness, which lifts the holder to the proper vertical position, and when thus elevated the lateral adjustment of the carriage and holder takes place by means of mechanism which will presently be described.

For the purpose of having the Jacquard harness raise the holder, a lever, *f*, is provided for each holder, to which a connection, *f'*, from the Jacquard harness is attached. The levers *f* are let into openings *d⁵* in the stems of the holders *D* at one end and pivoted to a portion of the carriage *E* at the other, while the connection *f'* is attached at some suitable point to the lever. The means for causing this elevation of the lever by the Jacquard harness will be presently explained. As soon as the holder 55 is raised by the Jacquard connection, a lateral adjustment of the frame or carriage *E* takes place to bring the holder in line with the shed of the warp-threads. This adjusting means consists of a pair of pushers, *g g*, mounted on a slide-bar, *g'*, and connected by cords *g^x g^x* to a drum, *G*, and wound in reverse directions on said drum. This drum is given a partial rotation in one direction at the elevation of each holder *D* by means of the crank-arm *G'*, pitman *G²*, and pivoted lever *G³*, which is operated on by a cam, *G⁴*, on a shaft, *H*, suitably driven by power. When the drum receives this

partial rotation, the pushers *g g* are caused to center upon the slide-bar *g'*, and will push the carrier or holder *D*, with the carriage in which it is held, into the space between the said pushers when thus drawn together, and hold it there until the drum is turned in the opposite direction and the pushers are released. This opposite movement of the drum 75 is accomplished automatically by a spring, *g⁵*, which is distended as the drum is being rotated to center the holder, as above described, and which will by its recoil throw the drum back into its normal position as soon as the 80 action of cam *G⁴* upon lever *G³* is completed.

As soon as the holder *D* is centered, as above described, the Jacquard connection may be released, and it is desirable that it should be released, so that the action of the Jacquard 85 harness may not be impeded nor delayed by having to sustain the holder from the said harness. For the purpose of supporting the holder when thus elevated and centered, so that the strain upon the Jacquard harness 90 may be released, I provide a vertically-moving supporting-stick, *D'*, which is caused to rise and rest under the lower end of the stem of the holder as soon as the same is centered. The lower end of the stem is hollowed out to 95 receive the rounded or pointed upper end of the stick *D'*. This stick *D'* is carried by a lever, *D²*, which is pivoted at its rear end, and is operated upon by a cam, *D³*, on the same shaft, *H*, with cam *G⁴*. The time of action of these cams is so regulated that the lever *G³* shall first be elevated, and then the lever *D²*. When the holder *D* is thus elevated and centered, the thrust-arm *I*, with nippers *I'*, is thrust forward or inward from 100 the opposite side of the warp-threads, and by means of the arrangement of jaws and spring-actuated stop or projection *I²* (shown in Fig. 4) the nippers are first opened to receive the weft-yarn between them, and then closed 105 upon it, and then drawn across between the warp-yarns. One jaw of nippers *I'* is provided with a projection, *i*, which comes into the path of the stop *I²* in the forward movement and opens the nippers. On the backward movement this stop is pushed out of the way by the projection *i*. The means for thus advancing and retracting the arm *I* consists of cords *c⁴* and *c⁵*, which are attached to the said arm and wound in opposite directions on 110 the drum *c^x*, mounted on a shaft, *c^{xx}*, which is rotated first in one direction and then in the other by means of the gear *c⁶* and segment *c⁷*, which is operated by a link, *c⁸*, from a crank, *c⁹*, on a shaft, *c¹⁰*, as shown in Fig. 2^a, 115 said shaft *c¹⁰* lying directly back of shaft *c^{xx}* in Fig. 2, and hence not showing therein.

As soon as the weft-thread is drawn across the warp-threads it is cut off at the holder end by means of a knife, *J*, which is held to 120 move vertically in guides *j j*, and is connected to an operating-arm, *J'*, which is connected at the lower end to a centrally-pivoted lever, *J²*, operated upon by a cam, *J³*, on a shaft, *K*,

suitably driven. The action of the cam raises the knife, and when it has passed its contact or high point the lever J^2 permits the knife to drop, which is accelerated and strengthened 5 or enforced by a spring, J^3 . The knife J thus presses upon the weft-thread, which rests upon a block or support, J^x , fixed in the frame of the machine and severs the thread, so that the holder may be dropped or moved side- 10 wise without affecting the thread which has been run into place between the warp-threads. The action of the knife is accurately timed to take place immediately upon the weft-thread d^x being drawn the entire width of the warp- 15 threads.

The weft-threads are drawn through guides D^x , held upon the carriage E , from suitable bobbins or spools. (Not shown.)

The construction of Jacquard harness by 20 which I achieve the movement of the holders D corresponds in the main particulars with the ordinary Jacquard harness well known in looms. Several features of novelty, however, have been added, which will appear in the 25 following description:

The needles 1^1 are suitably suspended, guided, and operated, and the cords 2^2 pass through eyes or loops in the needles in the ordinary manner. The cords are fastened 30 loosely in a perforated board at top by being knotted over said board. They are also provided with knots 3 at the point where they pass through a vertically-reciprocated board, 4 . This vertically-reciprocated board 4 is provided with openings 5 , which permit the knots 3 to pass, and with slots 6 , opening into said holes or openings 5 , which will not permit the knots 3 to pass. The slots 6 lie on the side of the holes next to the pattern-cards. With 40 all of cords 2 hanging in said slots, so that the forward movement of the pattern-carriage will move all of the needles forward, (except the one that goes through the hole in the pattern-card,) the said forward movement 45 of said carriage will move the needles forward and take all of the cords out of slots 6 except the one in the needle which goes through the hole in the pattern-card. This permits all the knots 3 to pass through the 50 openings 5 in board 4 except the knot on the string, which goes through the needle which has passed through the hole in the pattern-card. This cord remaining in the slot, the knot will remain on the upper surface of 55 the slotted middle board, 4 , and when said board is raised this cord will be raised or pulled up, which will raise the connection f' and elevate the holder D , as before described.

The vertical reciprocation of board 4 is ac- 60 complished by arms 4^a , extending from the rock-shaft 4^b , (suitably operated, as hereinafter described,) and link 4^c , connected with board 4 . The operation of the rock-shaft 4^b is accomplished by means of a pitman, 4^d , 65 connected to an end extension of one of the arms 4^a , as shown in Fig. 1, which pitman extends down to the operative parts of the loom

mechanism below and is thereby moved. The pitman 4^d extends down and is attached to a lever, 4^e , as shown in Fig. 1, and the lever is 70 worked by suitable crank or cam on shaft H , as shown in Fig. 2.

The pattern-card 7 is made of a continuous length of card-board or material of which loom-cards are usually made, and is held upon roll 7^a , mounted on a frame or support, 8 . The card 7 is provided with a line of perforations at bottom and top, which are taken hold of by projections 9 on the feed-roller 10 , by which the card is held and moved. After 80 passing over this feed-roller, the pattern-card sheet is passed under small roller 11 , over large roller 12 , and onto winding-up roll 13 , which latter is mounted on a pivoted arm, 14 , which is caused to hold roll 13 against roller 85 12 with sufficient pressure to cause it to be rotated by a spring, 15 . A shield, 16 , is placed between roller 10 and the card-sheet, over which the sheet is caused to progress. This shield is shown more fully in Fig. 9. It is provided with a series of holes, 17 , into which the needles, when they have passed through the pattern-holes in the card-sheet, are protruded. A reciprocatory movement toward and away from the needles is given to frame 8 by means 95 of the arms 8^a , which project through the frame of the Jacquard harness and are reciprocated by the arms 18 , connected to rock-shaft 19 , which is operated by pitman 19^a from the driving-shaft below. The connection or pitman 19^a extends down and is attached to a lever, 4^f , which is worked by a suitable cam or crank on shaft H , as shown in Fig. 2.

The feed-roller 10 and roller 12 are operated by a train of gearing, 20 , to which is connected a ratchet-wheel, 21 , in which a pawl, 22 , which is attached to the fixed part of the frame of the Jacquard harness, works, and the backward-and-forward movement of the card-carriage 110 causes the ratchet-wheel to be turned step by step, which, through the gearing above described, gives a progressive step-by-step movement to the card.

For ordinary use the card is made about 115 twelve holes deep. When more than twelve colors are required, instead of increasing the depth of said row of needles, and thus necessitating an increased width of the pattern-card, additional rows of needles are added and a 120 sidewise motion given to the carriage holding the pattern-card. This sidewise movement is accomplished by using the bottom or lower three needles in each row of needles for operating the device which shifts the pattern- 125 card carriage sidewise.

As shown in Fig. 10, three rows of needles are used. As shown in this figure, the cords 2 from the second and third horizontal line of needles, counting from the bottom, are attached to vertically-sliding bars 24 and 25 , which have wedge-shaped cams or projections 24^a on the upper ends thereof. These wedge-shaped cams or projections operate against the

side of the arms 8^a of the pattern-card frame 8, thus forcing it sidewise and bringing the vertical row of holes in shield 16 opposite the proper row of needles. When it is required to bring the pattern-carriage back, the bars 24 25 are forced downward by means of a pivoted lever, 26, by means of the cords 2, which pass through the bottom line of needles.

The restoration of the pattern-carriage is accomplished by springs 8^b, as shown in Figs. 7 and 8, which, being compressed by the action of the cams upon the bars 8^a, recoil when the bars 24 and 25 are lowered and move the carriage over.

15 The cam on one of the bars—for instance, 24—is smaller than that on 25, so that the movement sidewise caused thereby will not be so great, and only throw the carriage sufficiently to the side to shift from one vertical row of needles to the next, while the larger cam will shift past one row and bring the shield 16, with its line of holes, into line with a row of needles two removes off. It is evident that any number of rows of needles may 20 thus be used. After each operation the carriage is brought back to the first row of needles by means of lever 26, to which the cords 2 of the lower line of needles pass, as already 25 explained.

30 The lever 26 is centrally pivoted, as shown, and has a cross-pin, 26^a, in the end or limb thereof opposite to the end to which cords 2 are attached. As this end of the lever is caused to descend, the cross-pin 26^a forces bars 24 and 25 downward until their cams 24^a and 25^a stand below the arm 8^a, when the arms will assume the lateral position shown in Fig. 10.

A larger number of cords are shown in 40 some of the figures of the drawings than there are yarn-holders; but it is to be understood that in practice there will be as many levers and cords f' and yarn-holders as there are cords, while for convenience of illustration I have shown only a few of the said 45 levers and yarn-holders.

Having thus described my invention, what I claim, and desire to secure by Letters Patent, is—

50 1. The combination, with a Jacquard mechanism, of a series of thread-holders, each being provided with a hinged holding or tension arm, and each having independent connection with the Jacquard mechanism and capable of 55 vertical adjustment thereby, and a laterally-adjustable carriage in which said holders are supported, as set forth.

2. A thread-holder and connections to a 60 Jacquard mechanism by which the same is raised, in combination with said Jacquard mechanism, a supporting-stick, and means, substantially as described, for raising it under the holder and supporting said holder thereby, as set forth.

65 3. A thread-holder and sliding carriage in which said thread-holder is mounted, and means for vertically adjusting them therein,

in combination with pushers and means for actuating them, substantially as described, for adjusting said carriage laterally.

4. A series of thread-holders, a sliding carriage, and means, substantially as described, for raising the holders separately, in combination with the pushers for centering the elevated holder and carriage, and means, substantially as described, for advancing the said pushers from the sides to the center, as set forth.

5. The combination, with a series of thread-holders, means for vertically adjusting them, 80 a stick for sustaining a raised holder in an elevated position, means for actuating said stick, pushers, and actuating devices therefor for centering a holder when raised, of an arm with nippers on one end, and means, substantially as described, for projecting the said arm from the opposite side of the warp-threads for seizing the thread and drawing it through between the said warp-threads.

6. The combination, with a series of thread-holders and means for elevating them separately, a stick to hold the raised holder elevated, and means for actuating the stick, of the nippers for carrying the thread across through the warp, means for actuating the 95 nippers, a knife and guides in which it works, connections and pivoted lever, and a cam for elevating the knife by acting on the lever and releasing the lever to let the knife drop, as set forth.

7. The combination, with a Jacquard mechanism and the vertically-movable thread-holders and laterally-sliding carriage in which they are held, of levers pivoted to the carriage and extended through the stems of the holders, 105 and connections to the Jacquard harness from said levers for raising the said holders separately, as set forth.

8. The combination, with a Jacquard mechanism, vertically-movable thread-holders, and 110 sliding carriage in which they are held, of levers pivoted at one end to a part of the carriage-frame and inserted through the stem of the holders, connections from the said levers to the Jacquard harness, pushers, and means 115 for actuating them, substantially as described, for centering the sliding carriage and the elevated thread-holder, as set forth.

9. The combination, with the laterally-adjustable carriage, thread-holders held therein, 120 and means whereby they are raised and dropped therein, of the pushers, cords connected to said pushers, a drum to which the cords are connected at the other end, and means, substantially as described, for giving 125 the drum a partial rotation and then returning it to the normal position, whereby the pushers are operated, as set forth.

10. The combination, with the pushers, the cords connected thereto, the drum to which the cords are connected at the other end, the crank-pitman, lever, and cam for partially rotating the drum, and the rod and spring for returning the drum to the proper normal po-

sition, of the thread-holders and means for raising them and sliding carriage, substantially as set forth.

11. A thread-holder for looms, consisting of 5 stem and grooved projection, as described, and having an opening or hole through the head thereof, and a pivoted arm which rests in the groove, substantially as set forth.

12. A pattern-card and supporting and feeding devices therefor, and shield with line of 10 perforations lying back of said card, and means, substantially as described, for moving the said parts sidewise, as set forth.

13. The combination of a pattern-card, supporting and feeding devices therefor, and a 15 shield having a line of perforations, with the needles, needle-cords and cord-lifting devices, and cam-bars actuated by said needle-cords

for moving the pattern supporting and feeding devices and the card and shield sidewise, 20 substantially as set forth.

14. The combination, with a laterally-movable card-carriage, card and feeding devices therefor, and shield having the line of perforations, of the needles, needle-cords and cord-lifting devices, and sliding bars having wedges 25 or cams thereon for moving the card-carriage and attached parts, said bars being connected to the needle-cords, as set forth.

In testimony whereof I affix my signature in 30 presence of two witnesses.

KEDAR HARTLEY.
